UNITED STATES PATENT OFFICE.

GUSS A. SWANSON, OF SEATTLE, WASHINGTON.

BUILDING-BLOCK.

1,097,148.

Specification of Letters Patent.

Patented May 19, 1914.

Application filed June 2, 1913. Serial No. 771,178.

To all whom it may concern:

Be it known that I, GUSS A. SWANSON, a citizen of the United States, residing at Seattle, in the county of King and State of Washington, have invented certain new and useful Improvements in Building-Blocks, of which the following is a specification.

This invention relates to improvements in construction blocks for the walls of buildings, and has for its object the provision of a novel system of wall construction employing blocks, each unit of which is provided with interfitting key-devices of simple and efficient character whereby a building wall of any desired size may be readily constructed by unskilled labor and which wall will be extremely strong and resistant to pressure or shock.

A further object of the invention is the provision of corner blocks of simple construction whereby the corner of a building may be made a particularly strong element of the wall and at the same time provide means for varying the joints between the blocks in the several courses whereby said joints will not coincide in adjacent courses.

With these ends in view, the invention consists in the novel construction of a system of blocks for building walls, and the combination and adaptation therewith of various specific devices and improvements, as will be fully described in the following specification, illustrated in the accompanying drawings, and finally set forth in the appended claim.

In said drawings, Figure 1 is a perspective view of a wall composed of blocks embodying my invention. Fig. 2 is a vertical cross section of the same. Figs. 3, 4, 5 and 6 are detached perspective views of the blocks embodying my invention.

Referring to said views, the reference numeral 1 indicates a standard unit block of my invention and is composed of a body 2 of approximately one-half the thickness of the wall and a key 3 integrally connected to the inner face 4 of said body and of substantially the same thickness. Said key extends longitudinally the full horizontal length of the body at equal distances from its top and bottom edges and having its extremities terminate in the same planes as side edge 6 of the body. The outer face 5 and said inner face 4 of the block are in parallel planes and said opposite vertical side edges 6 are in parallel planes rectangular to said faces 4 and 5. Said top and bottom edges 7 and 7¹, respectively, are oppositely inclined at an angle converging toward the outer face 5 of the body. Said key 3 is formed with its upper and lower edges 8, 8¹ in angular relation to its outer face 9 respectively converging inwardly at the same inclinations as the edges 7, 7¹; said key thus forming a dove-tailed projection from the body 2 of the block. Said inner face 9 of the key is approximately one-half the width of the outer face 5 in vertical directions. Said block is a typical unit of construction and is utilized to a greater extent than any other form in the construction of a wall. In the building of a wall, however, various other shapes of blocks are required. A foundation block 10 is illustrated in Fig. 3. It is substantially a one-half section of the block 1, as will be clearly seen in Fig. 2. In addition to its respective portions similar to the same relative parts of block 1, and bearing the same reference numeral, the block 10 is formed with a plane bottom edge 11 rectangular to the side edges 8⁰ 6 and walls 4 and 5. In inverted position, said block also affords a coping or finishing block as seen at the top of said view.

In constructing a wall of separate block elements, as in the present invention, it is desirable that the joints between the blocks in a course do not coincide with the joints between the blocks of the adjacent courses. To provide for thus breaking the joints of the several courses and to provide for the construction of an exceptionally strong and interlocked corner at each of the salient angles of the building additional special corner blocks are utilized. An angle block 12, see Fig. 5, is formed with two integral body portions 2¹ arranged rectangularly to each other which are each about one-half the length of the body of a standard block 1. A key 3¹ is formed on the inner face of said angle block filling out the interior angle 100 formed by the inner faces of said bodies. The upper and lower faces of said key are formed symmetrically upon either side of their medial diagonal line, as 13, with inclined surfaces corresponding in angle and direction with the adjacent edges 7 or 7¹ thereof. Supplementing said angle-blocks in the construction of a corner are miter-blocks 14, see Fig. 6, which are substantially similar to the blocks 1 excepting that one of their vertical side edges, as 6¹, is formed on a miter of approximately forty-five de-

grees from the outer surface 5. The outer surfaces 5 of blocks 14 are of the same length as the blocks 1 while the inner surface length is reduced by said miter.

5 In building, the corners of one course are formed by the angle-blocks 12, and in the next superposed course two miter-blocks 14 are placed thereover with their mitered edges 6¹ contacting and by their greater lengths 10 extending over the lateral side edges 6 of the blocks 12 thereby covering the joint in the blocks below and have their mitered joints covered in turn by the blocks 12 therebelow and immediately above in the next 15 course. The manner of constructing a wall with blocks of my invention is believed to be obvious from the foregoing description.

After the foundation course, composed of blocks 10, has been laid, a course of blocks 20 1 is positioned thereon with a suitable mortar or cement filling therebetween. The blocks in each course are laid with their corresponding exposed faces 5 or 9 facing in the same direction and the next course above 25 is laid oppositely interfitting with the course below and breaking joints between the blocks in the several courses, as described. The topmost course may be composed of a row of blocks 10 inverted to form a coping, 30 as shown and described.

Other blocks of various sizes and designs for special offices and for the production of

special architectural effects may be made, employing the inventive idea of constructive and interlocking features, as herein set forth, and in so far as they are included within the scope of the appended claims they are contemplated in my invention.

The invention is particularly adapted to the construction of buildings in localities subject to seismic or cyclonic disturbances owing to the interlocked and stable character of its elements.

What I claim as my invention, is--

In a system of interlocking building blocks, a corner block having two integral body portions arranged rectangularly to each other, the upper and lower edges of which are formed with inclined surfaces arranged in converging angles to the outer surface thereof, and an integral key positioned in the interior angle formed by said body portions and having its upper and lower faces arranged symmetrically upon opposite sides of their medial diagonal line with inclined surfaces corresponding in angle and direction with said edges of the respective bodies.

Signed at Seattle, Wash., this 24th day of May, 1913.

GUSS A. SWANSON.
